LACE FABRIC OR SIMILAR ARTICLE

William Usdin, North Bergen, N. J., assignor to Swisscraft Embroidery Company, West New York, N. J., a partnership composed of William Usdin, Archie Usdin, and Ida Usdin

Application March 2, 1954, Serial No. 29,287

Term of patent 3½ years

(Cl. D47—6)

To all whom it may concern:

Be it known that I, William Usdin, a citizen of the United States, and a resident of North Bergen, county of Hudson, State of New Jersey, have invented a new, original, and ornamental Design for Lace Fabric or Similar Article, of which the following is a specification, reference being had to the accompanying drawings, forming a part thereof.

Fig. 1 is a top plan view of the lace fabric showing my new design with the complete design unit enclosed between the dot and dash lines.

Fig. 2 is an enlarged cross-sectional view taken at 2—2 of Fig. 1.

I claim:

The ornamental design for lace fabric or similar article, substantially as shown.
